UNITED STATES PATENT OFFICE.

SILAS L. GLADISH AND JAMES T. DE ARMOND, OF OSCEOLA, ARKANSAS.

BREATH-GUARD.

1,249,377.

Specification of Letters Patent. Patented Dec. 11, 1917.

Application filed January 31, 1916. Serial No. 75,464.

To all whom it may concern:

Be it known that we, SILAS L. GLADISH and JAMES T. DE ARMOND, citizens of the United States, residing at Osceola, in the county of Mississippi and State of Arkansas, have invented certain new and useful Improvements in Breath-Guards, of which the following is a specification.

This invention relates to breath guards and has as its object to provide a device of this class which may be readily applied and removed and which in use will not prove uncomfortable to the wearer. The primary aim of the invention is to provide a device of this class which will be entirely sanitary and will not interfere with respiration although effectually guarding against the inhalation of another's breath, the device being especially designed for use by barbers, physicians, dentists, etc.

In the accompanying drawings:

Figure 1 is a perspective view of the device embodying the present invention;

Fig. 2 is a vertical sectional view there-
25 through on the line 2—2 of Fig. 1;

Fig. 3 is a horizontal sectional view on the line 3—3 of Fig. 2.

The device embodying the present invention includes a body member which is indicated in general by the numeral 1, the said member being preferably formed from glass although any other suitable material may be employed. In marginal contour the body 1 is reniform, the body being preferably continuously and uniformly curved from its upper to its lower edge. The lower edge of the body, indicated by the numeral 2, is convex, and the upper edge, indicated by the numeral 3, is concave throughout its intermediate portion although toward the ends of the body this edge is convexed, as at 4, to merge with the ends of the convex edge 2. When the device is in use the lower edge thereof will rest upon the upper lip of the wearer and the end of the nose will be re-

ceived within the concavity of the edge 3 and in order that the device may be held in place, means is provided which will now be described.

The attaching means above referred to is 50 in the nature of a clip, the same comprising an intermediate or attaching portion, indicated by the numeral 5 and spaced side or gripping portions, indicated by the numeral 6. A screw or other suitable fastening element 7 is secured through the attaching portion 5 and the central portion of the body 1. It is preferable that the gripping portions 6 be tapered in the direction of their free ends and the said ends of the said 55 portions 6 are turned back upon themselves and against the inner faces of the respective portions 6 to form knobs or buttons 8 which may engage firmly against the opposite sides of the partition wall of the nose with- 60 out, however, causing inconvenience or injury such as would be likely to result if sharp edges were present. By reference to the drawings it will be observed that the at- 65 taching clip is secured to the rear or con- 70 cave face of the body member 1.

Having thus described the invention, what is claimed as new is:

In a device of the class described, a body member of substantially reniform marginal 75 contour, the said body member being continuously outwardly curved from its upper to its lower edge, the marginal contour of the body defining, at the upper edge of the said body, spaced lobes and an intermediate 80 recess, and an attaching means comprising a clip and a connecting attaching portion secured to the concave inner face of the guard member below the recess in the upper edge thereof and having spaced engaging 85 portions.

In testimony whereof we affix our signatures.

SILAS L. GLADISH. [L. S.]
JAMES T. DE ARMOND. [L. S.]
